US00D548973S

(12) **United States Design Patent** (10) **Patent No.:** **US D548,973 S**
Dawson et al. (45) **Date of Patent:** **** Aug. 21, 2007**

(54) **MOLDED CONTAINER**

(75) Inventors: **Kevin W. Dawson**, Charleroi, PA (US); **Peter Hess**, Venetia, PA (US); **Mathias L. Weinzen, Jr.**, Coal Center, PA (US)

(73) Assignee: **Rose Plastic USA, LP**, California, PA (US)

(**) Term: **14 Years**

(21) Appl. No.: **29/253,539**

(22) Filed: **Feb. 8, 2006**

(51) **LOC (8) Cl.** **03-01**

(52) **U.S. Cl.** **D3/302**; D3/300; D3/272; D9/711

(58) **Field of Classification Search** D3/201, D3/203.2, 203.5, 206, 269, 272-273, 293, D3/300, 302, 905; D9/504, 520, 529, 538, D9/711; D23/266; D28/89; 206/372, 379
